WELL CLEANING DEVICE

James J. Santiago, Los Angeles, Calif., assignor
to John Grant, Los Angeles, Calif.

Application May 20, 1935, Serial No. 22,297

23 Claims. (Cl. 166—19)

This invention has to do generally with well cleaning devices and is more particularly concerned with such devices wherein there is provided a low-pressure-holding or charge-receiving chamber with a normally closed inlet adapted to be opened at a predetermined point in the well whereby the well fluid, under relatively high pressure, charges that chamber with sand or other foreign matter adjacent the inlet, or sets up such pressure actions or high velocity fluid movements as to dislodge foreign matter which may be offering obstruction to free passage of fluid through fissures in the formation or perforations in the well casing.

15 While the invention is here described in connection with a device having a single-charge low-pressure chamber adapted to be emptied after each charging and after the tool has been lifted from the well, it will be understood the illustrated means for opening the chamber to receive well liquid and the control mechanism may be applied with advantage to the inlet of any type of low pressure chamber, irrespective of the manner in which the charged chamber is subsequently emptied or prepared for re-charge, and therefore the showing of the invention as embodied in connection with a particular type of chamber is not to be considered as limitative on such broader aspects of the invention.

30 In this connection it is to be noted that in dislodging foreign matter from casing perforations or otherwise promoting fluid flow by setting up fluid movement by the charging of the receiving chamber, (as distinguished from "bailing") the matter so dislodged is ordinarily, but not necessarily, forced into the charge receiving chamber and subsequently disposed of along with the fluid charge.

The device will here be described as utilized in 40 the cleaning of casing perforations, to which use it is particularly well adapted, but this particularized description is not to be considered as in any way limitative on the adaptability of the device for other cleaning operations.

45 Conditions under which it is desirable or necessary to perform well cleaning operations are so well known to workers in the art that it will be unnecessary here to detail them. However, it is well recognized that cleaning devices of the general nature set forth above must have certain characteristics, not easy of attainment, in order that they may be capable of performing efficiently and surely the services required. For instance, it is highly important that the inlet to the low pressure chamber be kept tightly closed until

the cleaner has reached the predetermined zone of operation and yet, in spite of that tight closure and in spite of the usually high fluid pressure in that zone, the inlet must be capable of practically instantaneous full-opening, under the control of the operator, after reaching that zone. Further, the control mechanism must not only be sure and fast in operation, but, to be fully efficient, must be of a nature which does not interfere with the rapid lowering or raising of the device to and from the zone of operation. Further, it must present little or no danger of accidentally opening the charge receiving chamber.

Therefore, it is among the general objects of the invention to provide a cleaner which shall 15 have the above desirable features, as well as others which may be pointed out to better advantage in connection with the detailed description to follow.

One of my major and more particular objects is 20 to provide a mechanism that will preclude the possibility of the charge receiving chamber being prematurely opened as the cleaner is being lowered in the well, and which is capable of repeated operation, without the necessity for removal from the 25 well, to open the charge receiving chamber in the event the mechanism fails to do so in the first operation. While, as will be understood, the invention broadly contemplates the use of various 30 different types of closures for the low pressure chamber whereby the latter may be opened to receive the charge of well fluid, I prefer to use a closure of the frangible disk type in which the disk is broken to suddenly place the charge receiving chamber in communication with the 35 well liquid, by the impact of a relatively movable disk breaking member. Also in accordance with my preferred form of the invention, I utilize a 40 disk breaking member of the spring loaded type in which the member is releasably held in cocked or retracted position, relative to the frangible disk, by a latch element, the latter being operable to release the breaking member, causing the latter to be projected against and to rupture the 45 disk.

While I do not claim as my invention broadly the use of a load-and-fire mechanism for opening communication with the charge receiving chamber, I have made various members and incorporated certain additional features in this 50 type of mechanism that characteristically distinguish the invention from similar types of mechanisms heretofore used, and in so doing have overcome various seriously objectionable features that have heretofore limited and interfered with 55

the successful operation of this type of well cleaner. For example, insofar as I am aware, prior well cleaning devices embodying a load-and-fire type of mechanism of the general character outlined above, have necessitated cocking or latching the firing member in retracted position before the cleaner is lowered in the well, with the result that frequently the firing or disk breaking member is prematurely released while the apparatus 5 is being lowered in the well due to sudden jarring or imparts caused by irregularities in the well. The invention entirely obviates the possibility of such occurrences due to the fact that the cleaner may be lowered to the desired position 10 with the breaking member out of cocked position, so that accidental release cannot occur. After the cleaner has been fully lowered, then the breaking member may be cocked and released 15 to break the disk and allow a sudden rush of well liquid into the low pressure chamber. The invention embodies a further highly desirable feature in that in the event the fire member fails in one operation to break the disk, it may be reset and released as many times as may be necessary 20 to finally break the disk, without having to remove the apparatus from the well.

The invention has many additional features and objects, but all these, as well as the aspects referred to above, will be best understood from 25 the following detailed description of certain typical and illustrative forms of the invention.

In the drawings:

Fig. 1 is a side elevation of a well cleaner embodying my invention;

Fig. 2 is an enlarged longitudinal section of an upper portion of the cleaner shown in Fig. 1, the disk breaking member being shown in a released position;

Fig. 3 is a continuation of Fig. 2 illustrating 40 the lower portion of the cleaner;

Fig. 4 is a view similar to Fig. 2 showing the disk breaking member in retracted position;

Fig. 5 is a sectional view showing the charge receiving chamber in the upper portion of the apparatus, Fig. 5 being an upper continuation of 45 the portion of the cleaner shown in Fig. 2;

Figs. 6 and 7 are sectional views similar to Figs. 2 and 3, respectively, showing the parts in charged position after the disk breaking member 50 has been released;

Fig. 8 is a section on line 8—8 of Fig. 2;

Figs. 9 and 10 are fragmentary side elevations showing the parts as viewed from lines 9—9 and 10—10 of Figs. 2 and 7, respectively;

Figs. 11, 12 and 13 are transverse sections taken on lines 11—11, 12—12, and 13—13, of Figs. 3, 4 and 6, respectively;

Fig. 14 is a fragmentary section on line 14—14 of Fig. 7;

Figs. 15 and 16 are sectional views similar to Figs. 2 and 3, showing a variational form of the invention;

Figs. 17 and 18 are fragmentary side elevations, partly in section, showing portions of the variant form as viewed from lines 17—17 and 18—18 of Figs. 15 and 16;

Fig. 19 is a fragmentary section on line 19—19 of Fig. 16;

Fig. 20 is a section on line 20—20 of Fig. 19;

Fig. 21 is a view, partly in section, showing the stirrup included in the mechanism of Figs. 15 and 16.

As has been previously stated, the cleaning device is particularly well adapted, but not limited,

to the dislodgment of foreign matter from the perforations of well casing, and therefore I have illustrated the device as positioned within such a perforated casing or screen C having any suitable type of perforations, here conventionally 5 illustrated at P.

The present cleaner construction may be regarded generally as comprising relatively longitudinally movable body and sleeve portions B and S, the lower portion of the body being in the 10 form of a mandrel M extending through the sleeve S, as will hereinafter more fully appear. The upper section of body member B is here shown to be made up of a plurality of sections coupled end-to-end, though it will be understood 15 that the showing of such sectional characteristics is not to be regarded as limitative on the invention.

Threadably connected body or casing sections are indicated at 10, 11 and 12 (see Fig. 5), section 10 serving as a head or top closure for the charge receiving or low pressure chamber 11a. Coupling 13 is threadably connected to section 10 and serves as means whereby the body may be attached to a suspension element, for example cable 14, see Fig. 1. Section 11, here shown as longitudinally contracted, may be of any desirable length and may, itself, be sectional. A forty foot length gives chamber 11a a capacity 20 ample for most operations.

Section 10 has a reduced axial bore 15 from which extends a transverse passageway 16 controlled by a spring-closed, outwardly opening valve generally indicated at 17. The function of this valve is merely to relieve high pressure in the charge receiving chamber as the tool is raised into zones of lower pressure. To facilitate unloading chamber 11a, after the latter has received a charge and the cleaner is removed from the well, I preferably provide an inwardly opening, spring-closed dump relief valve 18. This valve is fully described and claimed in Patent No. 2,059,629, issued November 3, 1936, to W. C. Erwin et al., on Well bailers, wherein the valve showing is substantially identical with the instant 30 showing. It will suffice here to state that screw plug 19 normally closes passageway 20. When chamber 11a is to be unloaded, plug 19 is removed and passageway 20 is then adapted to put the chamber into communication with the atmosphere when the lower pressure in the chamber (as created by dumping the fluid), is of a value allowing spring closed valve 18 to open under atmospheric pressure.

Screwed into the lower end of section 12 is 55 a section 21 whose bore 22 may be considered as the inlet opening of chamber 11a, the upper end of 21 presenting an upward facing seat 23 to take a foot valve 24. Pin 25 acts as a stop to limit the upward movement of valve 24. Section 12 is also provided with a removable dump door 26 the construction and mounting thereof being fully described and claimed in the above mentioned Patent No. 2,059,629, wherein the showing of the door is substantially the same as the instant showing. The door is opened by loosening screws 27 (which normally press the door inwardly to compress gasket 28 and provide a fluid-tight seal), and then sliding the door transversely to clear lugs 29 from overhanging lips 30, 60 which latter define way 31.

Section 21 has counterbores 33 and 34, containing a bushing 35 below which is a member 36 carrying a frangible disk 37. As best shown in Fig. 8, the disk carrying member 36 is inserted 75

into the body below bushing 35 within a transverse slot 36a in the body. The mounting and disposition of the disk is fully described and claimed in said Patent No. 2,059,629 wherein the 5 showing of these features is substantially the same as the instant showing. Disk 37 may be made of any suitable frangible material, such as glass or other ceramic composition, and has a downwardly concave shape, as illustrated, so as 10 to be readily engageable by the disk breaking member hereinabove described. It suffices to note at this point that disk 37 normally provides a fluid-tight bottom closure for the charge receiving chamber 11a, and that the cleaner is 15 lowered in the well with chamber 11a empty. After the cleaner has been lowered to the depth of the well zone to be cleaned, the cleaning operation is then performed by breaking disk 37 to allow a sudden rush of well liquid through the 20 casing perforations P and openings in sleeve S into the low pressure chamber 11a, as will later be brought out.

Provision is made whereby the disk carrying member 36 may be releasably locked within the body, and yet rendered removable for replacement of the disk without the necessity for having to disconnect the body sections, by placing on body section 21 a rotatable sleeve 32 supported between body rings 321, there being a pin 38 25 projecting from the body through a horizontally extending slot 110 in the sleeve. The construction is best shown in Fig. 2 wherein the sleeve 32 has been shown, for purposes of illustration, to be rotated substantially 90° in the direction 30 of the arrow, to more clearly illustrate its slotted formation. In reality, when the cleaner is lowered in the well, the sleeve will be rotated to the position of Fig. 6, as will be explained. The disk carrier member 36 is inserted within and with- 35 drawn from the body through the sleeve slot 111 registering with body slot 36a. In order to permit member 36 to be withdrawn through slot 111 after a cleaning operation with the disk breaking member 46 projected up through member 35 in 40 the later described position of Fig. 6, I provide in sleeve 32 a slot 112 registering with a correspondingly shaped slot 112a (Fig. 1) in the body section 21, through which a pin (not shown) may be inserted within one of the openings 113 in 45 the disk breaking member. By means of the inserted pin, the disk breaking member may be pulled down against the resistance of spring 50 sufficiently to enable member 36 to be withdrawn through slot 111, and another disk carrying mem- 50 ber with an unbroken disk, inserted within the body. Sleeve 32 is then rotated to the left, as viewed in Fig. 2, to lock member 36 in place, bringing slots 111 and 112 around to the positions shown in Fig. 6, which position is determined by 55 the engagement of pin 38 with the end of the horizontal slot 110.

The lower end of section 21 is threadably connected at 39 with body section 40, the latter in turn being connected by screwthreads 41 with 60 the reduced diameter lower tubular section 42 of the body, previously referred to as the mandrel portion M of the body. The lower end of this mandrel section 42 is closed by a screwthreaded member 43, the bottom of which is tapered as at 65 44 to facilitate passing any obstructions that might be encountered within the casing while the cleaner is being lowered.

The low pressure chamber opening mechanism, generally indicated at 45, comprises a disk break- 70 ing member 46, preferably though not necessarily 75

of tubular form, adapted to be projected against the frangible disk 37 when released by the latch device generally indicated at 47. The head 46a of tubular member 46 preferably is tapered to avoid fluid constriction within bore 34, and if 5 desired, the upper end of this head portion may be provided with teeth 48 to more effectively rupture the disk when projected thereagainst.

Member 46 normally (see Fig. 2) is supported in engagement with the disk 37 by a coil spring 10 50 contained within a cup-shaped liner 51 inserted within body section 21 and seating on the upper end of section 40. As shown in Fig. 13, the bottom flange of liner 51 has a series of openings 51a to permit fluid circulation between the liner 15 and the outside of member 46. Spring 50 bears upwardly against a shoulder 52 on the head 46a of member 46. Lugs 53 project radially beyond shoulder 52 to guide member 46 within bore 54 of the body, and serve as stops to limit the longitudinal travel of the member within the body by engagement with the upper end of liner 51, when member 46 is in cocked position and with body shoulder 54a when the member is in fully projected position. 20 25

The latch 47 comprises a sleeve 55 screw-threaded at 56 on the upper end of a tube 57 depending within the upper portion of the mandrel 42, tube 57 having a sliding fit within the mandrel bore and being longitudinally movable with- 30 in the body. Downward movement of latch sleeve 55 and tube 57 relative to the body is resisted by a coil spring 58 confined between the upper end of mandrel 42 and the bottom of sleeve 55. 35

Latch sleeve 55 is longitudinally slotted for a short distance downwardly from its upper end to form, radially expandable detents 55a having on their upper ends projections 59 which are engageable with an annular shoulder 60 formed on the 40 lower end of tubular member 46. Detents 55a have sufficient clearance at 61 from the wall of body section 40 to permit radial expansion of projections 59 to the extent of releasing shoulder 60 and member 46 for upward movement, as will 45 presently appear. Upon upward movement of the body relative to sleeve 55 from the positions of Fig. 2 to Fig. 4, detent shoulders 62 come into engagement with annular surface 63 on shoulder 60, the angularity of surfaces 62 and 63 being such that 50 the latch will retain the disk breaking member until spring 50 will be compressed to the point at which lugs 53 come into engagement with the upper end of liner 51. Surfaces 62 and 63 may 55 have any suitable angularity greater than the slip angle, though in practice an angle of around 30° has been found satisfactory. The angularity of surfaces 64 on the detents 55a and surfaces 65 on member 46 preferably will be somewhat greater, for instance around 60°, in order that there will 60 be no undue resistance to movement of member 46 from the projected position of Fig. 6 back into retained engagement by the latch, as in Fig. 2, as the body is lowered to reset the disk breaking member in the manner hereinafter described. 65

The sleeve structure S comprises a tube 66 carrying a pair of longitudinally spaced packers generally indicated at 67 and 68, which may be of any suitable type and construction capable by engagement with the casing C, of confining between them an annular space 69 through which suction is applied to the casing perforations P opposite the space when the charge receiving chamber is opened, as hereinafter described. As typical, I have shown the packers 67 and 68 each 70 75

to comprise a cup leather or rubber 70 confined within a supporting annulus 71 clamped against shoulder 72 on the sleeve 66, by spacer sleeves 73 and 74, the latter in turn being held in place by nuts 75. The packers engage the casing with sufficient tightness to hold the sleeve assembly against substantial vertical movement in the casing during operation of the cleaner, as will fully appear later. Nuts 77 and 77a having rounded end surfaces 77b are threaded on the upper and lower ends of tube 66.

As best illustrated in the cross sectional view of Fig. 11, opposite sides of the mandrel portion 42 of the body are flattened at 78 to form with sleeve 66, longitudinal by-pass passages 79 extending the full length of the sleeve. Between passages 79, the mandrel 42 has a fairly snug and substantially fluid-tight sliding fit with sleeve 66. Latch tube 57 is connected with sleeve 66 by means of a transverse pin 80, see Fig. 14, extending through the lower end of the tube and terminating in the sleeve. Relative longitudinal movement between the body and sleeve assembly, including with the latter the latch tube 57, occurs within the limits of engagement of nut 77a on the upper end of sleeve 66 with the lower end of body portion 40, see Fig. 9, and the engagement of nut 77 on the bottom of the sleeve with the mandrel nut 43, as shown in Fig. 10. During such relative longitudinal movement between the mandrel and sleeve, pin 80 travels longitudinally within slots 81 in the mandrel. However, in order to preclude the possibility of the pin becoming sheared while the apparatus is going into or coming out of the well, slots 81 are extended somewhat beyond the limiting positions of the pin 80, see Fig. 14, when the sleeve and mandrel are in their extreme relative positions corresponding to Figs. 2 and 7.

The mandrel 42 is chamfered at 82 and 83 at both the upper and lower extremities of flattened surfaces 78 so that in the uppermost and lowermost positions of the mandrel relative to the sleeve 66, these by-pass passages will remain in open communication with the interior of the casing through the openings 84 and 85, see Figs. 9 and 10, formed by the chamfers 82 and 83. At this point it may be particularly noted that in all operating positions of the cleaner, and throughout the range of relative movement between the body B and sleeve assembly S, the by-pass passages remain open. The purpose of these passages is of course to provide for the by-passing of well liquid past the packers 67 and 68 as the cleaner is lowered or raised in the well and to eliminate fluid resistance to such movements.

Opposite sides of the intermediate portion of sleeve 66 between packers 67 and 68 have longitudinal slots 86, the edges of which are beveled as indicated by the surface at 87, see Figs. 3 and 11. Through these slots, suction is communicated to the surrounding space 69 between the packers by way of the mandrel bore 88 and a series of mandrel ports 89, see Fig. 11, registering with the sleeve slots 86. Some of the uppermost ports 89 may be in registration with slots 86 when the mandrel is in its lowermost position relative to the sleeve, see Fig. 3, but when the mandrel has been raised to its uppermost position, substantially as illustrated in Fig. 7, all the ports 89 are brought to register with the slots 86. Pin 80 prevents relative rotation between the mandrel and sleeve, and keeps slots 86 and ports 89 in longitudinal alignment.

In operation, the cleaner is lowered into the well with the parts in the position shown in Figs.

2 and 3, the disk breaking member 46 having been inserted within the latch 47 but remaining in an uncocked or out of retracted position. The sleeve assembly S is forced downwardly through the casing against the resistance of packers 67 and 68, by the engagement of the intermediate body section 40 with nut 77b on the upper end of sleeve 66. During downward movement of the cleaner through the well liquid standing in casing C, the liquid is by-passed upwardly past the packers through the open passages 79. The apparatus is lowered in the well until space 69 between the packers is brought opposite the particular portion of the perforated casing to be cleaned.

By reason of the fact that the cleaner is lowered with the disk breaking member 46 in uncocked position, and with provision made for substantial lost motion between the parts before the member can be moved to a retracted or cocked position, the possibility of the low pressure chamber opening mechanism being accidentally tripped while the cleaner is being lowered, is practically precluded. This will be seen upon consideration of the fact that if obstructions are encountered that would tend to temporarily hold up and then cause the sleeve and latch assembly to suddenly drop relative to the body, still such movement would not trip the disk breaking member. This is true because, first, of the resistance of spring 58 to downward movement of the latch sleeve to the trip position, and second, due to the lost motion afforded by the necessity for the detent 59 to move downward from the position of Fig. 2 to the point of engagement with shoulder 60, and member 46 to be subsequently pulled down to the point where lugs 53 engage the upper end of liner 51, before the disk breaking member can be cocked and the latch released to project it against the disk 37.

After the apparatus has been lowered to proper position for the cleaning operation, the body B is raised to progressively elevate shoulder 60 into engagement with the detents 59 and to raise liner 51 into engagement with lugs 53, as shown in Fig. 4. Upon continued upward movement of the body, the latch is released from the disk breaking member and the latter is projected upwardly, by the expansive force of spring 50, to engage and break the disk 37, see Fig. 6. Due to the suddenness of the disk breaking operation, the low pressure chamber 11a is instantly placed in full communication with space 69 in the casing between the packers, and a sudden suction is applied to the casing perforations P causing any clogging particles, together with well liquid, to be drawn into the low pressure chamber through the full registering slots 86 and ports 89, and thence upwardly through the latch tube 57 and the breaking member 46.

As previously mentioned, if for any reason the member 46 fails to break the disk in one operation, it may be reengaged within the latch and again projected against the disk as many times as may be required to fracture the latter. The resetting operation is accomplished merely by lowering the body from the position of Fig. 6 to that of Fig. 2, so as to thrust the lower shouldered end of member 46 into the latch sleeve 55, thus resetting the disk breaking mechanism for another operation as above described. Immediately upon breaking the disk 37, the charge is drawn upwardly into the chamber 11a, unseating valve 24, until a pressure balance exists. Thereupon the ball valve 24 seats, and the cleaning operation is completed so that the cleaner

may now be pulled from the well with the charge trapped in chamber 11a. In elevating the cleaner, the sleeve S is pulled upwardly with the body by the engagement of nut 11 on the bottom of the sleeve by the mandrel nut 43, by-pass passages 79 remaining open all the while to obviate any resistance to removal by the presence of the hydrostatic column of liquid in the well.

In Figs. 15 to 21, I show a variational form of the invention similar in its general construction and mode of operation to the previously described form, but differing in the construction of the mandrel and in additional provisions for rendering the apparatus proof against accidental tripping while the cleaner is being lowered in the well. In the views showing the variational form of the invention, parts similar to corresponding parts in the first described form are designated by the same numerals with primes 20 added.

Referring to Figs. 15 to 18, the mandrel M', is shown to include an inner tube 42' and an outer sleeve 90 having a fluid-tight fit with the tube 42' except where opposite surfaces 78' of the latter have been flattened to form by-pass passages 91 as in the first described form. Sleeve 90 is confined between the lower end of body section 40' (see Fig. 17) and nut 43' (see Fig. 18) on the lower end of the mandrel, the sleeve terminating within annular recesses 92 and 93 and being locked by set screws 94. Openings 95 and 96 are formed in the upper and lower ends of the sleeve 90 and mandrel 42' at the ends of mandrel surfaces 78' in order to provide constantly open communications between the ends of by-pass passages 91 and the interior of the casing.

In this form of the invention, the by-pass passages are contained entirely within the mandrel 40' itself, as distinguished from the first described form in which the corresponding passages are directly between the packer carrying sleeve and the mandrel. Sleeve 90 has a freely sliding fit with sleeve 66', the necessity of providing a fluid-tight fit between the sleeves not being as important as the desirability for a close fit between the mandrel and sleeve in the first described form, due to the fact that with the by-pass passages confined within the sleeve part of the mandrel, a substantially greater sealing surface contact is maintained between the relatively moving parts.

Ports 98 drilled through the sleeve 90 and mandrel 42', are adapted to be brought into registration with longitudinally extending slots 99 formed in opposite sides of the sleeve 66', when the mandrel is raised to uppermost position determined by the engagement of nut 43' with nut 100 on the lower end of the sleeve. A stirrup 102, best illustrated in Fig. 21, is connected to the lower end of latch sleeve 55' by a collar 103 attached to the top of the stirrup and threaded into the lower end of the latch sleeve. Stirrup 102 depends within the mandrel section 42' of the body, and has intermediate its ends a bridge portion 102a adapted to be brought into engagement with the pin 104, see Fig. 19, which extends through the lower opening 102b of the stirrup, mandrel slots 81', and terminates in the sleeve 56'.

As in the described form, a coil spring is placed within body section 40' between latch sleeve 55' and the upper end of the mandrel section 42'.

In operation, starting with the parts in the positions shown in Figs. 15 and 16, upward movement of the body first raises the stirrup 102 to

the point where pin 104 is brought into engagement with the bottom of the stirrup at the lower end of opening 102b. It will be noted that until pin 104 engages the lower end of the stirrup, no relative movement occurs between the latch mechanism and the disk breaking member, in distinction to the first described form wherein, by reason of the latch being integrally connected with the sleeve, the latch starts to move relatively toward the lower end of the disk breaking member at the start of upward movement of the body. Thus in this variational form, I have in effect provided for additional lost motion in the disk breaking member operating mechanism, the extent of lost motion being the length of opening 102b in the stirrup, or the distance which pin 104 must move relatively before the latch sleeve 55 starts its downward relative movement within the body to cock the disk breaking member.

Upon further upward movement of the body and mandrel, stirrup 102 is first raised to the point where pin 104 is engaged at the lower end of opening 102b. With latch sleeve 55' held against further upward movement, member 46' is raised to the point of engagement between detents 59' and shoulder 60'. Subsequent upward travel of the body cocks the disk breaking member and releases it to be projected against the disk, all in the manner previously described.

By reason of the additional lost motion afforded by the pin and slot connection 104, 102b, between the latch and sleeve 66', further assurance is had against accidental tripping of the disk breaking member while the cleaner is being lowered into the well. Thus, if for any reason the sleeve assembly tends to suddenly drop on the mandrel, pin 104 must lower to the point of engagement with the bottom of the stirrup before the latch can move relatively to the breaking member to move the latter toward cocked position. In order to provide a yielding resistance to upward movement of the body relative to the stirrup after the latter has been raised to the point of engagement with pin 104, the length, longitudinally of the body, of spring 58' preferably is adjusted so that the lower end of sleeve 55' will come into engagement with the spring at substantially the time when the lower end of the stirrup engages pin 104.

In Fig. 15, I have shown the inclined surfaces 64' of detents 59, and also surface 65' on shoulder 60', to have a different angularity than the corresponding surfaces 64 and 65 of the first described form, in order to increase the resistance to reengagement of shoulder 60 within the latch after the member 46' has been projected against the disk 37'. In this last form, surfaces 64' and 65' may have an angularity in the neighborhood of 45°, or of any other suitable value that will increase the resistance of resetting to the extent that if member 46' fails to break the disk, shoulder 60' will be supported sufficiently on the detent surfaces 64' to enable the body and disk 37' to be suddenly dropped down against the upper end of member 46' to break the disk, without necessarily having to force the breaking member into retained engagement by the latch.

I claim:

1. In a well cleaning device, a body forming a low pressure chamber, normally closed means adapted to be opened to admit well liquid to said chamber, a member movable relative to said body from retracted to projected position to open the first mentioned means, means for releasably

holding said member in retracted position, and a suspension means on which said body is lowered into the well, said member being movable from non-retracted position to retracted position and 5 into retained but releasable engagement with said holding means after said body has been lowered in the well.

2. In a well cleaning device, a body forming a low pressure chamber, normally closed means 10 adapted to be opened to admit well liquid to said chamber, a member movable relative to said body from retracted to projected position to open the first mentioned means, means for releasably holding said member in retracted position, and a suspension means on which said body is lowered into the well, and means operable by movement of 15 the suspension means for moving said member from non-retracted position to retracted position and into retained but releasable engagement with 20 said holding means, after said body has been lowered in the well.

3. In a well cleaning device, a body forming a low pressure chamber, normally closed means 25 adapted to be opened to admit well liquid to said chamber, a member movable relative to said body from retracted to projected position to open the first mentioned means, a suspension means on which said body is lowered into the well, and means independent of said suspension means for 30 releasably holding said member in retracted position, said member being releasable from and reengageable with said holding means by raising and lowering said suspension means.

4. In a well cleaning device, a body forming a low pressure chamber, normally closed means 35 adapted to be opened to admit well liquid to said chamber, a member movable vertically relative to said body from retracted to projected position to open the first mentioned means, a suspension means on which said body is lowered into the well, and means independent of said suspension means for 40 releasably holding said member in retracted position, said member being releasable from and reengageable with said holding means by raising and lowering said body.

5. In a well cleaning device, a body forming a low pressure chamber, normally closed means 50 adapted to be opened to admit well liquid to said chamber, a member movable relative to said body from retracted to projected position to open the first mentioned means, yieldable means resisting movement of said member from projected to retracted position, means for releasably holding said member in retracted position, and a suspension means on which said body is lowered into the well, said member being movable from non-retracted position to retracted position and into 55 retained but releasable engagement with said holding means after said body has been lowered in the well.

6. In a well cleaning device, the combination comprising, an apertured sleeve, means holding said sleeve in engagement with the well casing, a body movable vertically relative to said sleeve 60 and containing a low pressure chamber, normally closed means adapted to be opened to admit well liquid through said sleeve to said chamber, a member movable relative to said body from retracted to projected position by virtue of upward movement of the body relative to the sleeve, to open said normally closed means, means associated with said sleeve for releasably holding said member in retracted position, and a suspension means on which said body and sleeve are lowered into the well, said member being movable 65

with the body from non-retracted position into retained engagement with said holding means, upon downward movement of said body relative to said sleeve.

7. In a well cleaning device, the combination 5 comprising, an apertured sleeve, means holding said sleeve in engagement with the well casing, a body movable vertically relative to said sleeve and containing a low pressure chamber, normally closed means adapted to be opened to admit well 10 liquid through said sleeve to said chamber, a member movable relative to said body from retracted to projected position by virtue of upward movement of the body relative to the sleeve, to open said normally closed means, a spring latch 15 connected to said sleeve for releasably holding said member in retracted position, and a suspension means on which said body and sleeve are lowered into the well, said member being movable with the body from non-retracted position 20 to retracted position and into retained engagement with said latch, upon downward movement of said body relative to said sleeve.

8. In a well cleaning device, the combination 25 comprising, an apertured sleeve, means holding said sleeve in engagement with the well casing, a body movable vertically relative to said sleeve and containing a low pressure chamber, normally closed means adapted to be opened to admit well 30 liquid through said sleeve to said chamber, a member movable relative to said body from retracted to projected position by virtue of upward movement of the body relative to the sleeve, to open said normally closed means, a latch movable 35 vertically relative to said sleeve for releasably holding said member in retracted position, means for limiting upward movement of the latch relative to the sleeve, and a suspension means on which said body and sleeve are lowered into the well, said member being releasable from said 40 latch by upward movement of said body relative to said sleeve, and being returnable into engagement with said latch by reverse relative movement between said body and sleeve.

9. In a well cleaning device, the combination 45 comprising, an apertured sleeve, means holding said sleeve in engagement with the well casing, a body movable vertically relative to said sleeve and containing a low pressure chamber, normally closed means adapted to be opened to admit well 50 liquid through said sleeve to said chamber, a member movable relative to said body from retracted to projected position by virtue of upward movement of the body relative to the sleeve, to open said normally closed means, a latch movable 55 vertically relative to said sleeve for releasably holding said member in retracted position, means for limiting upward movement of the latch relative to the sleeve, and a suspension means on which said body and sleeve are lowered into the well, said member being releasable from said 60 latch by upward movement of said body relative to said sleeve, and being returnable into engagement with said latch by reverse relative movement between said body and sleeve, there being 65 within said sleeve a by-pass passage that is open at all relative positions of the body and sleeve.

10. In a well cleaning device, a body forming 70 a low pressure chamber, a frangible element closing one end of said chamber, a member movable longitudinally within said body from retracted to projected position to engage and break said element, and a latch comprising a yieldable element engaging said member to hold it in retracted position, and means for moving said 75

member from non-retracted position into retracted position while the device is lowered in the well.

11. In a well cleaning device, a body forming a low pressure chamber, a frangible element closing one end of said chamber, a member movable longitudinally within said body from retracted to projected position to engage and break said element, and a latch engaging said member to hold it in retracted position, and means for moving said member from non-retracted position into retracted position while the device is lowered in the well, said member being engageable with and releasable from said latch by straight longitudinal movement relative thereto.

12. In a well cleaning device, a body forming a low pressure chamber, a frangible element closing one end of said chamber, a tubular member movable longitudinally within said body from retracted to projected position to engage and break said element, said member being adapted to pass well fluid into said chamber when said element is broken, and a latch comprising a yieldable element engaging said member to hold it in retracted position, and means for moving said member from non-retracted position into retracted position while the device is lowered in the well.

13. In a well cleaning device, a body forming a low pressure chamber, a frangible element closing one end of said chamber, a member movable longitudinally within said body from retracted to projected position to engage and break said element, yieldable means resisting movement of said member from projected to retracted position, and a latch engaging said member to hold it in retracted position, and means for moving said member from non-retracted position into retracted position while the device is lowered in the well.

14. In a well cleaning device, a body forming a low pressure chamber, a frangible element closing one end of said chamber, a member movable longitudinally within said body from retracted to projected position to engage and break said element, a shoulder on said member, and a latch engaging said member to hold it in retracted position and comprising a detent engageable with and releasable from said shoulder by straight relative longitudinal movement between said member and detent.

15. In a well cleaning device, a body forming a low pressure chamber, a frangible element closing one end of said chamber, a member movable longitudinally within said body from retracted to projected position to engage and break said element, a latch engaging said member to hold it in retracted position, and means for moving said member from non-retracted position into retracted position while the device is lowered in the well, yieldable means resisting relative movement between said latch and the body, and yieldable means resisting movement of said member from projected to retracted position.

16. In a well cleaning device, the combination comprising, an apertured sleeve, means holding said sleeve in engagement with the well casing, a body movable vertically relative to said sleeve and containing a low pressure chamber, normally closed means adapted to be opened to admit well liquid through said sleeve to said chamber, and means for opening the last mentioned means by virtue of relative longitudinal movement between said body and sleeve, there being a by-pass passage between the body and sleeve that remains open throughout said relative movement.

17. In a well cleaning device, the combination comprising, an apertured sleeve, means holding said sleeve in engagement with the well casing, a body movable vertically relative to said sleeve and containing a low pressure chamber, normally closed means adapted to be opened to admit well liquid through said sleeve to said chamber, means for opening said normally closed means, the last mentioned means comprising a latch and a closure opening member movable into and out of retained engagement with said latch by relative movement of said body and sleeve.

18. In a well cleaning device, a body forming a low pressure chamber, normally closed means adapted to be opened to admit well liquid to said chamber, a member movable relative to said body from a cocked position to a projected position to open said means, yieldable means resisting movement of said member into cocked position, a latch for releasably holding said member in cocked position, and means for cocking said member after the device is lowered in a well with said member in uncocked position.

19. In a well cleaning device, a body forming a low pressure chamber, normally closed means adapted to be opened to admit well liquid to said chamber, a member movable relative to said body from a cocked position to a projected position to open said means, yieldable means resisting movement of said member into cocked position, a latch for releasably holding said member in cocked position, and means operable by vertical movement of said body for bringing said latch into holding engagement with said member after the device is lowered in a well with said member in uncocked position.

20. In a well cleaning device, an apertured sleeve, spaced packers carried on said sleeve and adapted to engage the well casing, a body movable vertically relative to said sleeve and forming a low pressure chamber, normally closed means adapted to be opened to admit well liquid through said sleeve into said chamber, a member movable relative to said body from a cocked position to a projected position to open said means, yieldable means resisting movement of said member into cocked position, a latch for releasably holding said member in cocked position, said latch being operable by relative movement between said body and sleeve after the device has been lowered in the well, to cock said member.

21. In a well cleaning device, an apertured sleeve, spaced packers carried on said sleeve and adapted to engage the well casing, a body movable vertically relative to said sleeve and forming a low pressure chamber, normally closed means adapted to be opened to admit well liquid through said sleeve into said chamber, a member movable relative to said body from a cocked position to a projected position to open said means, yieldable means resisting movement of said member into cocked position, a latch for releasably holding said member in cocked position, said latch being operable by relative movement between said body and sleeve after the device has been lowered in the well, to cock said member, and the latch being engageable with said member when the latter is in uncocked position and then having substantial vertical movement relative thereto before acting to cock said member.

22. In a well cleaning device, an apertured sleeve, spaced packers carried on said sleeve and adapted to engage the well casing, a body movable vertically relative to said sleeve and forming a low pressure chamber, normally closed

means adapted to be opened to admit well liquid through said sleeve into said chamber, a member movable relative to said body from a cocked position to a projected position to open said means, yieldable means resisting movement of said member into cocked position, a latch for releasably holding said member in cocked position, said latch being operable by relative movement between said body and sleeve after the device has been lowered in the well, to cock said member, and yieldable means resisting relative vertical movement between said latch and the body.

23. In a well cleaning device, an apertured sleeve, spaced packers carried on said sleeve and adapted to engage the well casing, a body movable vertically relative to said sleeve and forming a low pressure chamber, normally closed

means adapted to be opened to admit well liquid through said sleeve into said chamber, a member movable relative to said body from a cocked position to a projected position to open said means, yieldable means resisting movement of said member into cocked position, a latch for releasably holding said member in cocked position, said latch being operable by relative movement between said body and sleeve after the device has been lowered in the well, to cock said member, and the latch being engageable with said member when the latter is in uncocked position and then having substantial vertical movement relative thereto before acting to cock said member, and yieldable means resisting relative vertical movement between said latch and the body.

JAMES J. SANTIAGO.
